UNITED STATES PATENT OFFICE

ADOLPH MAEULEN, OF WILLIAMSPORT, PENNSYLVANIA, ASSIGNOR TO WILLIAMSPORT MIRROR & GLASS CO., OF WILLIAMSPORT, PENNSYLVANIA, A CORPORATION OF PENNSYLVANIA

VENTILATOR

Application filed March 5, 1930. Serial No. 433,380.

This invention relates to improvements in ventilators, and more especially to a novel adjustable bracket to be employed in holding a glass plate or the like at the sill portion of 5 a window frame for ventilating purposes.

Heretofore, it has been proposed to hinged-ly connect a glass panel or the like to a window sill, so as to prevent any direct draft when the lower sash is slightly raised, and it 10 is the primary object of the present invention to improve the brackets used with such ventilators.

Another object of the invention is to provide a ventilator bracket which may be in- 15 expensively manufactured from sheet metal, and which will effectively grip an end of the ventilating panel or plate.

A further object is to furnish a ventilator bracket including a bearing plate provided 20 with a stop lug which will function to limit the swinging movement of the panel toward the sash.

Another object is to provide a stamped sheet metal ventilator bracket including a 25 channel portion designed to grip an edge of the ventilating panel, one side of the channel portion being stamped out to furnish a slotted guide that cooperates with the swinging arm of the bracket.

With the foregoing objects outlined and 30 with other objects in view which will appear as the description proceeds, the invention consists in the novel features hereinafter described in detail, illustrated in the accom- 35 panying drawing, and more particularly pointed out in the appended claims.

Referring to the drawing,

Fig. 1 is an elevation of a portion of a 40 window frame and ventilator, the latter being provided with the improved bracket.

Fig. 2 is a vertical sectional view of the same on a reduced scale, and showing the panel gripped by the bracket.

Fig. 3 is a similar view on an enlarged scale, and showing the bracket in two positions, with the panel omitted.

Fig. 4 is a horizontal sectional view of a portion of the window frame, and a top plan 50 view of the bracket.

Fig. 5 is a sectional view of a detail on the line 5—5 of Fig. 3.

Fig. 6 is a similar view, enlarged, of a portion of the structure shown in Fig. 5.

Fig. 7 is a front elevation of a modifica- 55 tion.

Fig. 8 is a sectional view thereof taken on line 8—8 of Fig. 7.

In the drawing, 10 designates a window frame, and 11 a lower sash slidably mounted 60 therein.

In accordance with the present invention, each side of the window frame is provided on its inner surface, just above the sill 12, with a bearing plate 13, which is of angular construction to provide a vertical stop lug 14. An arm 16 is pivotally mounted on the plate 13 by any suitable fastening means, but it is preferred to employ a screw 17 for this purpose, so that the screw not only functions as 70 a pivot pin, but also acts to fasten the parts 13 and 16 to the window frame.

As best shown in Fig. 5, each arm 16 is provided at its outer end with a rigidly connected screw 18 which passes through a slot 75 19 that is formed in a wing 20 which is integral with a channel-shaped part 21. This part has converging side walls 22 and 23, and in manufacturing the improved bracket, the wing 20 is stamped or cut from the wall 22, 80 thereby leaving an opening 24.

As the channel-shaped part and its wing 20 are formed of sheet metal, it will be appreciated that the extremities of the walls 22 and 23 may be pushed toward one another, 85 so as to cause the extremities to grip an end of a ventilating panel 25. This panel may be of any suitable rigid material, either transparent, translucent or opaque, but it is preferred to make the same of glass. 90

A thumb nut 26 engages the screw 18, and acts to clamp the wing 20 to the arm 16, so that the panel may be held in any desired position of adjustment. In Fig. 3, in full lines, the bracket is shown at the inner limit of its 95 movement, while in dotted lines, it is shown engaging the stop lug 14, which limits the forward movement of the panel.

As best shown in Figs. 1 and 3, the lower end of the channel-shaped portion of each 100

bracket is pivotally connected by a screw 27 to the window frame, and whenever the bracket is adjusted, it will turn on the screw 27.

5 While only one bracket has been illustrated, it will be obvious that a similar bracket is used at the opposite end of the panel 25.

With a construction of this character, the brackets may be sold separately in a hardware store or the like, and the purchaser can 10 then use with the same, a panel 25 of any suitable material.

It will be manifest that the present bracket is of simple and inexpensive construction, 15 and is one which is not liable to get out of order in use. Besides, it may be attached to a window frame and may be adjusted by an unskilled person.

From the foregoing, it is believed that the 20 construction, and advantages of the invention may be readily understood, and it is apparent that changes may be made in the details disclosed, without departing from the spirit of the invention, as expressed in the 25 claims.

In the modified form of Figs. 7 and 8, the wing 20' is welded or brazed to the wall 22' and provided with a slot 19 as in the preferred form permitting the use of a rolled 30 channel bar comprising walls 21', 22' and 23'.

What I claim and desire to secure by Letters Patent is:

1. A window ventilator bracket, comprising 35 a channel-shaped member having a slot extending parallel to the channel, and a pivotally mounted arm having a fastening device slidably mounted in said slot.

2. A window ventilator bracket comprising 40 a channel-shaped member provided at one end with means for pivotally connecting the same to a window frame, said member having an elongated slot extending parallel to the channel, a pivot pin adjustably mounted in the slot, an arm having one of its ends connected to the pivot pin, and means for pivotally connecting the other end of said arm to a window frame.

3. A window ventilator bracket including 50 a channel-shaped member made up of a web and opposite side walls, means for pivotally connecting said member to a window frame, one of said walls being cut to provide a slotted tongue arranged in substantially the same plane as the web.

55 4. A window ventilator bracket including a channel-shaped member made up of a web and opposite side walls, means for pivotally connecting said member to a window frame, one of said walls being cut to provide a slotted 60 tongue arranged in substantially the same plane as the web, a pivot pin passing through said slot, an arm connected to the pivot pin, and means for pivotally connecting said arm to a window frame.

65 5. A window ventilator bracket including

a channel-shaped member made up of a web and opposite side walls, means for pivotally connecting said member to a window frame, one of said walls being cut to provide a slotted tongue arranged in substantially the same plane as the web, a pivot pin passing through said slot, an arm connected to the pivot pin, means for pivotally connecting said arm to a window frame, and a stop lug 70 connected to the last mentioned means for limiting the movement of said member in one direction. 75

6. A window ventilator bracket, comprising 80 a channel-shaped member provided at one end with means for pivotally connecting the same to a window frame, said channel-shaped member including a web and opposite side walls, a wing rigidly united with said member, arranged in substantially the same plane as the web, and provided with a slot positioned parallel to the channel, a pivot pin passing through said slot, an arm connected to said pivot pin, and means for pivotally connecting the arm to a window frame. 85

7. In a ventilator, a bracket comprising 90 a channel-shaped member provided at one end with means for pivotally connecting the same to a window frame, said member including a web and opposite side walls, one of said walls being cut to provide a wing positioned in the same plane as the web, said wing having an elongated slot arranged parallel to the channel-shaped member, an arm, a threaded fastening including a portion extending through said slot, and means for 100 pivotally connecting said arm to a window frame.

In testimony whereof I affix my signature.

ADOLPH MAEULEN.
